MULTIFILAMENT ELECTRIC LIGHT BULB

Nick Zagmester, Niagara Falls, N. Y.

Application June 7, 1937, Serial No. 146,887

8 Claims. (Cl. 176—27)

This invention relates to certain new and useful improvement in multi-filament electric light bulb.

The primary object of the invention is to provide a multi-filament bulb having a body or casing formed of glass and of any shape desired, the same being preferably of heart-shape with a double inner partition wall with the outer faces of the partition wall mirrored to increase light reflecting characteristics.

A further object of the invention is to provide a multi-filament bulb of the foregoing character with a switch device in the base of the bulb for selectively or simultaneously activating the filament.

With the above and the other objects in view that will become apparent as the nature of the invention is better understood, the same consists in the novel form, combination and arrangement of parts hereinafter more fully described, shown in the accompanying drawings and claimed.

In the drawings:—

Figure 1 is a longitudinal sectional view of a multi-filament electric light bulb constructed in accordance with the present invention, showing the outer casing and inner double walled partition with separate filaments in the casing at the inner and outer sides of the partition;

Figure 2 is a fragmentary longitudinal sectional view of the base portion of the bulb showing one arm of the multiple-switch device closing a pair of contacts for a circuit to one filament;

Figure 3 is a fragmentary longitudinal sectional view, similar to Figure 2, and showing another arm of the multiple-switch device closing another pair of contacts for a circuit to the other filament;

Figure 4 is a fragmentary longitudinal sectional view of the base portion of the lamp with the multiple-switch device shown in elevation;

Figure 5 is a cross-sectional view taken on line 5—5 of Figure 1, showing one filament between the outer wall of the bulb and the inner partition;

Figure 6 is a cross-sectional view taken on line 6—6 of Figure 1, showing a circular series of hollow ball members carried by the outer side of the double wall partition;

Figure 7 is a cross-sectional view taken on line 7—7 of Figure 1, showing the oppositely disposed contacts for the two filaments;

Figure 8 is a cross-sectional view taken on line 8—8 of Figure 1;

Figure 9 is a cross-sectional view taken on line 9—9 of Figure 1;

Figure 10 is a longitudinal sectional view on an enlarged scale of the multiple-switch device for operating the separate contacts for closing 5 circuits to the two filaments;

Figure 11 is a cross-sectional view taken on line 11—11 of Figure 10;

Figure 12 is a cross-sectional view taken on line 12—12 of Figure 10;

Figures 13 and 14 show two side elevational views of the block carrying two resilient contact arms to be selectively and simultaneously operated by the multiple-switch device;

Figure 15 is a side elevational view of a key-piece for mounting in the blocks carrying the resilient contact arms;

Figures 16 and 17 show side and top plan views respectively of a diametrically notched plate in the base of the lamp bulb through which the 20 resilient contact arms extend;

Figures 18, 19 and 20 show side elevational views, partly in section of three parts of the multiple-switch device; and

Figure 21 is a diagrammatic view of the wiring arrangement for the two filaments.

The multi-filament electric light bulb includes a glass shell 1 substantially of heart-shape as shown in Figure 1 with a tapering neck 2 that will hereinafter be referred to as the base of 30 the lamp or bulb, the vitreous base 2 being covered by a tapering metallic casing 3 threaded to the base as at 4 and externally threaded at the end thereof as at 5 for mounting in a lamp socket. The metallic casing 3 is anchored to the 35 base 2 by means of screws 6 and nut and bolt combinations 7, the base 2 comprising an outer end separate section 2a to facilitate mounting of the metallic casing to the base.

A double-walled partition within the shell 1 of substantially bell-shape is formed integral with the base section 2 and includes inner and outer walls 8 and 10 integrally formed at the ends adjacent the outer end of the shell 1 as 40 at 11 with the walls 8 and 10 diverging towards the base section 2, the inner end 12 of the inner wall 8 being integral with a block 13 formed in the hollow base section 2 while the inner end of the outer wall 10 of the partition is integral with the base section 2 as clearly shown in Figure 1 of the drawings. Openings 14 and 15 formed in the block 13 as the result of the molding operation facilitate vacuumizing of the shell 1 and area between the partition walls 8 45 50 55

and 10 and said openings are closed by solder plugs 16.

The inner face of the partition wall 9 and the outer face of the partition wall 10 are mirrored to increase reflecting characteristics and for additional reflection and ornamental features, the outer wall 10 of the partition adjacent the base section 2 carries a circular series of hollow spherical ball-like projections 17 that may be 10 suitably colored if desired, the heart-shaped shell 1 carrying an annular enlargement 1a in the form of an outward bulge in line with the circular series of ball-like projections 17. The open end of the bell-shape partition is further supported within the shell 1 by struts 18 of glass.

A filament 19 is located within the inner wall 9 of the double-walled partition and a filament 20 is located in the shell 1 surrounding the double-walled partition. As shown in Figure 6, 20 the filament 19 is supported at spaced points on the wall 9 by pins 21 while the filament 20 as shown in Figure 5 is supported at the base points on the outer wall 10 of the partition by spaced pins 22. The wiring for the filaments 19 and 25 20 as shown in Figures 1 to 6 and 21 includes a conductor 23 extending through a portion of the base section 2 with one end anchored in a contact 24 communicating with the chamber 25 in the base section 2 while the other end communicates with a pin 26 attached to one end of the filament 19, said pin 26 being anchored in an enlarged portion of the wall 9. A pin 27 anchored in the wall 9 and attached to the other end of the filament 19 is in communication with 35 the conductor 28 extending to a portion of the base section 2 for engagement with the element 29 that is grounded to the metallic casing 15.

The wiring arrangement for the resistance 26 includes a pair of pins 30 and 31 mounted in the 40 wall 10 of the bell-shaped member and respectively attached to adjacent ends of the filament 20, the pin 30 being connected to a conductor 32 that extends to a portion of the base section 2 for attachment to the contact 33 in the chamber 25. A conductor 34 is attached to the pin 31 and extending through a portion of the base section 2 is grounded as at 35, on the metallic casing 15.

The pair of movable contacts is associated with 50 the contacts 24 and 33 and as shown in Figures 1 to 4 and 13 to 17, a tapering block having stepped portions 36 and 37 formed of conducting material and carrying a terminal 38 exposed at the base of the lamp is mounted in a socket in 55 the base section 2a, the section 36 of the conductor block carrying a pair of resilient contact arms 39 and 40 that extend into the chamber 25 in normally spaced relation to the contacts 24 and 33 as diagrammatically illustrated in Figure 21. 60 To anchor the conductor block within the socket in the base section 2 against rotation, the section 36 of the conductor block is provided with a rectangular socket 41 opening toward the chamber 25 for the reception of the removable rectangular block 42 shown in Figure 15 as having 65 rectangular socket 43 in its lower end to receive a rectangular key projection 44 rising from a disk 45 shown in detail in Figures 16 and 17 and which disk is suitably anchored at the inner end 70 of the chamber 25 in the base section 2. The disk 45 is diametrically notched as at 46 for passage of the resilient contact arms 39 and 40.

A multiple-switch device for operation of the resilient contact arms 39 extends across the chamber 25 and is journaled in the opposite side

walls of the base section 2 and metallic casing 15 and as shown in Figures 1 to 4, 10, 11 and 18 to 20, the multiple-switch device comprises a cylindrical shaft 47 having an annularly reduced portion 48 intermediate its ends with one end further annularly reduced and externally threaded as at 49, the cylindrical shaft comprising the sections 47, 48 and 49 having a bore 50 extending longitudinally therethrough that is rectangular in cross-section as shown in Figures 11 and 12. 10 The larger portion 47 of the shaft carries a disk head 51 at its outer end and the bore 50 is closed by the wall 52 apertured as illustrated for purposes presently to appear. Spanner wrench openings 53 are formed in the outer face of the 15 disk head 51. An internally threaded sleeve 54 is threaded onto the threaded end 49 of the shaft 47 and moves into abutting engagement with the adjacent end of the annularly reduced portion 48 of the shaft 47, the larger portion of the shaft 20 47 and the sleeve 54 being of the same diameter as illustrated in Figures 4 and 10. A disk head 55 is carried by the outer end of the sleeve 54 and is provided with spanner wrench openings 56 25 in its outer face, the disk head 55 having a central opening 57 therein communicating with the bore 50 in the shaft 47.

A rod 58 rectangular in cross-section is dimensioned for sliding interfitting engagement in the bore 50 in the shaft 47, one end of the rod 58 30 carrying a disk 59 that is engaged with the disk head 55 on the sleeve 54 with a finger piece of handle 60 on the rod 58 outwardly of the disk 59. The other end of the rod 58 engages the closure wall 52 in the disk head 51 carried by the 35 shaft 47 and said rod 58 as shown in Figure 20 has a threaded socket 61 at the end thereof adjacent the wall 52 to receive the headed screw 62 passed through the apertured wall 52, the headed screw 62 and the disk 59 upon the rod 58 40 co-acting to hold the shaft 47 and sleeve 54 in assembled relation. The multiple-switch device extends transversely of the chamber 25 in the base 2 and the disk heads 51 and 55 rest in seats in the outer sides of the metallic casing 15 as 45 shown in Figure 4, with the switch device disposed between the resilient contact legs 39 and 40 as shown in Figures 1 to 3. An insulation block 63 in the form of a sleeve is anchored to the annularly reduced portion 48 of the shaft 47 50 and is clamped between the adjacent end of the sleeve 54 and the adjacent shouldered end of the shaft portion 47, the insulation sleeve 63 carrying four radially extending switch fingers, two of the fingers 64 being diametrically opposite, 55 while the other two fingers 65 and 66 extend at acute angles to one of the fingers 64 as shown in Figures 1 to 3.

From the above detailed description of the invention, it is believed that the same will at once be understood, it being noted that when the switch device is rotated by means of the finger piece or handle 60, both switch fingers 64 may be simultaneously engaged with the resilient contact arms 39 and 40 for moving them into engagement with the stationary contacts 24 and 33 for simultaneously illuminating the filaments 19 and 20. Other rotary movements of the switch device selectively place the fingers 65 and 66 in contact with the resilient contacts 39 and 40 70 respectively for selective illumination of the filaments 19 and 20.

While there is herein shown and described the preferred embodiment of the invention, it is nevertheless to be understood that minor changes 75

may be made therein without departing from the spirit and scope of the invention as claimed.

I claim:-

1. In a multi-filament electric light bulb, a bulb casing and a base, a bell-shaped double walled member therein, a filament in the bell-shaped member and a filament in the casing surrounding the bell-shaped member, and switch mechanism in the base for selective and simultaneous illumination of the filaments.
2. In a multi-filament electric light bulb, a bulb casing and a base, a bell-shaped double walled member therein, a filament in the bell-shaped member and a filament in the casing surrounding the bell-shaped member, switch mechanism in the base for selective and simultaneous illumination of the filaments, the outer faces of the bell-shaped double wall member having a reflecting coating and a circular series of ball-like hollow projections carried by the outer wall of the bell-shaped member, the switch mechanism including a pair of fixed contacts in the base of the lamp respectively communicating with the filaments, a pair of resilient contact arms, a shaft journalled transversely of the lamp base, and radial switch fingers carried by the shaft for moving the resilient contact arms into engagement with the fixed contacts.
3. In a multi-filament electric light bulb, a bulb casing and a base, a bell-shaped double-walled member therein, a filament in the bell-shaped member and a filament in the casing surrounding the bell-shaped member, switch mechanism in the base for selective and simultaneous illumination of the filaments, the switch mechanism including a pair of fixed contacts respectively communicating with a filament, a pair of cooperating resilient contact arms and a rotatable member carrying switch fingers for moving the resilient contact arms into engagement with the fixed contacts.
4. In a multi-filament electric light bulb, a bulb casing and a base, a bell-shaped double-walled member therein, a filament in the bell-shaped member and a filament in the casing surrounding the bell-shaped member, switch mechanism in the base for selective and simultaneous illumination of the filaments, the outer faces of the bell-shaped double wall member having a reflecting coating and a circular series of ball-like hollow projections carried by the outer wall of the bell-shaped member, the switch mechanism including a pair of fixed contacts respectively communicating with a filament, a pair of cooperating resilient contact arms and a rotatable member carrying switch fingers for moving the resilient contact arms into engagement with the fixed contacts.
5. In a multi-filament electric light bulb, a bulb casing and a base, a bell-shaped double-walled member therein, a filament in the bell-shaped member and a filament in the casing surrounding the bell-shaped member, switch mechanism in the base for selective and simultaneous illumination of the filaments, the switch mechanism including a pair of fixed contacts in the base of the lamp respectively communicating with the filaments, a pair of resilient contact arms, a shaft journalled transversely of the lamp base, and radial switch fingers carried by the shaft for moving the resilient contact arms into engagement with the fixed contacts, the journalled shaft including a pair of threadedly connected members, each having a head at its outer end positioned exteriorly of the lamp base and engaged therewith.
6. In a multi-filament electric light bulb, a bulb casing and a base, a bell-shaped double-walled member therein, a filament in the bell-shaped member and a filament in the casing surrounding the bell-shaped member, switch mechanism in the base for selective and simultaneous illumination of the filaments, the outer faces of the bell-shaped double wall member having a reflecting coating and a circular series of ball-like hollow projections carried by the outer wall of the bell-shaped member, the switch mechanism including a pair of fixed contacts in the base of the lamp respectively communicating with the filaments, a pair of resilient contact arms, a shaft journalled transversely of the lamp base, and radial switch fingers carried by the shaft for moving the resilient contact arms into engagement with the fixed contacts, the journalled shaft including a pair of threadedly connected members, each having a head at its outer end positioned exteriorly of the lamp base and engaged therewith.
7. In a multi-filament electric light bulb, a bulb casing and a base, a bell-shaped double-walled member therein, a filament in the bell-shaped member and a filament in the casing surrounding the bell-shaped member, switch mechanism in the base for selective and simultaneous illumination of the filaments, the switch mechanism including a pair of fixed contacts in the base of the lamp respectively communicating with the filaments, a pair of resilient contact arms, a shaft journalled transversely of the lamp base and radial switch fingers carried by the shaft for moving the resilient contact arms into engagement with the fixed contacts, the journalled shaft including a pair of threadedly connected members, each having a head at its outer end positioned exteriorly of the lamp base and engaged therewith.
8. In a multi-filament electric light bulb, a bulb casing and a base, a bell-shaped double-walled member therein, a filament in the bell-shaped member and a filament in the casing surrounding the bell-shaped member, switch mechanism in the base for selective and simultaneous illumination of the filaments, the outer faces of the bell-shaped double wall member having a reflecting coating and a circular series of ball-like hollow projections carried by the outer wall of the bell-shaped member, the switch mechanism including a pair of fixed contacts in the base of the lamp respectively communicating with the filaments, a pair of resilient contact arms, a shaft journalled transversely of the lamp base, and radial switch fingers carried by the shaft for moving the resilient contact arms into engagement with the fixed contacts, the journalled shaft including a pair of threadedly connected members, each having a head at its outer end positioned exteriorly of the lamp base and engaged therewith.

NICK ZAGMESTER.
